UNITED STATES PATENT OFFICE

H. MITCHELL GODSEY, OF SALT LAKE CITY, UTAH

SECTIONAL FLUID HEATER

Application filed May 5, 1930. Serial No. 449,997.

My invention relates to fluid heaters, boilers or vaporizers particularly of the sectional type.

One object of my invention is to provide an apparatus of this character which is more efficient than prior apparatus, but which is relatively simple and inexpensive to manufacture and install.

A further object of my invention is to provide an improved heater or boiler of the counter-flow type, in which the products of combustion traverse the apparatus in the opposite direction from the direction of flow of the fluid to be heated.

Another object of my invention is to provide, in a sectional heater or boiler, integral baffles for directing the flow of heating gases therethrough.

A still further object of my invention is to provide an improved fluid heater or boiler containing baffles which are arranged to be filled with fluid to be heated, whereby the baffles are cooled and the efficiency of heat transfer in the apparatus is enhanced.

Other objects and advantages of my invention will be clear from a consideration of the specific embodiments thereof shown on the accompanying drawings. Although liquid heaters are shown and described herein, the invention is applicable to air heaters, for example, and the term "fluid" is intended to include both liquids and gases.

In the drawings, Fig. 1 is a longitudinal sectional view through a heater or boiler embodying the invention, a part of the casing of the boiler sections being broken away to illustrate the construction more clearly;

Figs. 2 and 3 are detailed sectional views on the section lines 2-2 and 3-3 of Fig. 1;

Fig. 4 is a transverse sectional view of the heater or boiler on the line 4-4 of Fig. 1;

Fig. 5 is a similar view illustrating the manner in which the size of the heater is increased by utilizing more sections;

Fig. 6 is a front view of the heater or boiler shown in Fig. 1, and

Fig. 7 is a plan view of one of the sections of the improved heater.

Referring particularly to Figs. 1, 5 and 6 of the drawings, the heater or boiler shown

comprises a number of units or sections, the end sections being designated by the reference numerals 1 and 2, and the intermediate sections by the reference numerals 3 and 4. As shown in Fig. 4, a small heater may comprise only one intermediate section 3. The several sections of the boiler may be constructed of cast iron and the engaging surfaces may be filed, sand-blasted or machined to form fluid-tight joints where such joints are required.

The sections of the heater are held together by truss rods or bolts 7 extending through integral lugs 8 upon the end sections 1 and 2 of the heater. The sections are mounted upon a base member 10 which serves to support heating means, such as gas burners 11, which are of any usual or known construction and are shown as connected to a gas manifold 12 and regulated by the usual valves 13. The outlet opening of the heater is connected to the usual stack or flue 15 through which the hot gases escape from the heater. Obviously, any desired heating apparatus may be used in connection with the heater, the gas burners being merely one practical form of such apparatus.

The sections of the heater, as shown in Fig. 1, comprise headers 16 and 17 at the ends thereof, the fluid to be heated being admitted through a pipe connection or threaded boss 18 to the header 16. The outlet for heated fluid or vapor is indicated at 19, an outlet being shown in each section 3 but all but one of the outlets may be closed by suitable plugs, if desired. Each outlet opening 19 communicates with the portion 20 of the heater constituting an enlargement or dome which in the case of a steam boiler may be termed the steam drum. Openings 21 are disposed adjacent to the drum 20 in the side walls of the sections to provide communication between the several sections of the heater.

The sections 3 and 4 of the boiler are further provided, as shown in Figs. 1 and 2, with fluid tubes 25 extending between the headers 16 and 17. The arrangement of the tubes 25 in the sections 4 are substantially the same as in the sections 3, as shown in Fig. 1, except that the tubes are in staggered relation with

those in the adjacent sections, as shown in Fig. 5.

Likewise the end sections 1 and 2 of the heater are provided with hollow portions 26 to contain the fluids to be heated. The inner surface of the sections 1 and 2 are corrugated as indicated at 27 to provide, as in the case of the adjacent sections 3 and 4, a tortuous passage for the hot products of combustion from the burners 10 between the fluid tubes, as indicated by the arrows 28 in Fig. 5. Obviously the precise dimensions and configuration of the surfaces of the heater sections and of the tubes 25 may be modified without departing from the scope of the present invention. The object of the construction shown is to provide the desired contact of the hot products of combustion with the walls of the fluid-containing elements of the heater through which heat transfer is effected.

The sections of the heater are further provided as shown in Fig. 1 with hollow bottom tubes 30 extending from the header 16 to the base member 10. The tubes 30 are of the same width as the sections so that they contact with each other when the heater is assembled, and close the combustion space at the bottom of the heater. A plurality of integral baffles are also provided in each section of the heater, two such baffles 31 and 32 being shown by way of example. These baffles are hollow, as indicated in Fig. 1, and are filled with the fluid to be heated, whereby the baffles are cooled and heat transfer is effected through the walls thereof. The baffle 31 extends from the drum 20 or upper portion of the heater to the bottom of the lower tube 25, leaving a space between the lower end of the baffle and the tube 30. Likewise the tube 32 extends from the drum 20 downwardly to the tube 30 and communicates with the latter.

The width of the tube 31 is the same as the width of each section, as shown in Fig. 2, whereby the abutting edges of the baffles are in contact when the heater is assembled and passage of the hot products of combustion is prevented except below the lower end of the baffle. As shown in Fig. 3, the lower end of the baffle 32 is of the same width as the width of the sections, but the upper end of the baffle between the upper tube 25 and the drum 20 is provided with a constricted portion 33. Thus a passage for hot products of combustion is provided between the upper tube 25 and the drum 20 adjacent the constricted portions 33 of the baffle.

Upon reference to Fig. 1, it will be apparent that the described construction provides three passages 34, 35 and 36 through which the hot products of combustion traverse the sections of the heater from the burners 11 to the stack 15. These passages are serially related and require the hot products of combustion to pass through the heater substantially counter-current to the flow of fluid

therethrough. In other words, the cold fluid entering the heater contacts with the partially cooled products of combustion and the flow of fluid and hot gases through the heater are in opposite directions, which results in a considerable increase in efficiency and is an important feature of my invention. As indicated in Fig. 1, the cross-sectional area of the passage for the hot products of combustion in general decreases from the burners 11 to the stack so that as the hot gases are cooled and decrease in volume, the rate of flow of the gases remains substantially constant. This is a desirable, though not an essential, feature of the invention.

The usual auxiliary apparatus may be used in connection with the heater, and as shown in Figs. 1 and 6, if the heater is designed for use as a steam boiler, a water gauge 38 and pressure gauge 39 are mounted upon one of the sections 3. Obviously, however, the apparatus is not limited to use for vaporizing water but may be used for heating other liquids, and the general principles may be embodied in air or gas heaters. Various modifications in the specific embodiment of the invention shown and described may be made without departing from the scope of the invention as indicated in the appended claims.

I claim:

1. A fluid heater comprising one-piece fluid-circulating sections arranged side by side to form a complete heater, each of said sections embodying an integral steam drum of substantially the same width as the section and two vertical integral abutting baffles arranged to direct the flow of the products of combustion upward, downward and upward again across the sections of the heater.

2. A fluid heater comprising one-piece fluid-circulating sections arranged side by side to form a complete heater, an intermediate section embodying horizontal fluid tubes and a plurality of vertical baffles intermediate the ends of said tubes arranged to direct the flow of the products of combustion several times across said horizontal fluid tubes, said intermediate section further embodying an integral dome at the top thereof of substantially the same width as the said section.

3. A fluid heater comprising cast-metal fluid-circulating sections arranged side by side to form a complete heater, an intermediate section thereof embodying in a unitary construction horizontal fluid tubes and a dome above said tubes and integral therewith and of the same width as the section, said intermediate section being further provided with vertical baffles arranged to direct the flow of the products of combustion back and forth across the entire section and substantially counter-current to the flow of fluid in the heater, said baffles extending substantially from the lowermost of said horizontal fluid tubes to said dome.

4. A fluid heater comprising fluid-circulating sections embodying horizontal fluid tubes and heating means adjacent one end of said tubes, said sections being provided with an integral steam drum at the top thereof and two hollow vertical baffles to direct the flow of the products of combustion substantially counter-current to the flow of fluid in the tubes, said hollow baffles extending to the steam drum and the interior thereof being in communication with said horizontal fluid tubes and the steam drum.

5. A fluid heater comprising fluid-circulating sections embodying horizontal fluid tubes and heating means adjacent one end of said tubes, said sections being provided with an integral steam drum at the top thereof and two integral vertical baffles intermediate the ends thereof, one adjacent said heating means and extending to the bottom of the heater section and the other spaced from the first baffle and extending to the top of the heater section, one of said baffles being hollow and in direct communication with at least one of said horizontal fluid tubes and the steam drum.

6. A fluid heater comprising fluid-circulating sections embodying horizontal fluid tubes, said sections being provided with an integral steam drum at the top thereof and two hollow integral vertical baffles intermediate the ends thereof, one extending to the bottom of the heater section and being in communication with at least one of said horizontal fluid tubes, the other baffle being spaced from the first-mentioned baffle and extending to the top of the heater section, said other baffle being in communication with at least one of said horizontal fluid tubes and with said integral steam drum.

7. A fluid heater comprising one-piece cast metal fluid-circulating sections arranged side by side to form a complete heater, each of said sections embodying horizontally disposed fluid tubes and an upper portion constituting a dome of the same width as the section to close the top of the heater, said dome being formed integral with said horizontal tubes and communicating therewith, and two vertically disposed baffles arranged to direct the heating medium upwardly, downwardly and upwardly again throughout the sections.

8. A fluid heater comprising one-piece fluid-circulating sections arranged side by side to form a complete heater, each of said sections embodying horizontally disposed fluid tubes and an integral dome or steam drum in communication with said tubes, the width of said dome or drum being equal to the width of the section whereby when the sections of the heater are assembled the dome or drum abuts against the adjacent sections to close the top of the heater.

9. A hollow cast-metal section for a heater comprising a hollow fluid-containing por-

tion, an integral steam drum of substantially the same width as the section and hollow fluid-containing baffles of substantially the same width as the drum and extending to said drum, said baffles being arranged substantially vertical and spaced apart from each other and from the ends of the section.

10. A cast-metal heater section comprising horizontally disposed fluid-circulating tubes spaced apart to provide passages for the heating medium, an integral steam drum at the top of the section and vertically disposed baffles arranged to direct the heating medium upwardly, downwardly and upwardly again over the tubes, said baffles extending substantially from the lowermost of said horizontal fluid tubes to said steam drum, and said steam drum being of substantially the same width as said section.

11. A cast-metal heater section comprising a fluid-containing portion, an integral enlargement at the top of the section in communication with said fluid-containing portion and constituting a steam drum of the same width as the section, and a plurality of vertical baffles intermediate the ends of the section, said baffles being arranged to define a gas-passage of decreasing cross-section for the hot gases flowing through the heater to maintain the velocity thereof substantially uniform.
